CLAIM

The ornamental design for a specimen cup holder with detachable handle, as shown and described.

DESCRIPTION

FIG. 1 is a perspective view of a specimen cup holder with detachable handle showing our new design, in a disassembled position;

FIG. 2 is a rear elevational view thereof, in assembled position;

FIG. 3 is a front elevational view thereof;

FIG. 4 is a side elevational view thereof;

FIG. 5 is a side elevational view thereof, opposite that shown in FIG. 4;

FIG. 6 is a top plan view thereof; and,

FIG. 7 is a bottom plan view thereof.
